US00D598670S

(12) **United States Design Patent**
Gelardi et al.

(10) **Patent No.:** **US D598,670 S**
(45) **Date of Patent:** **** Aug. 25, 2009**

(54) **DISC HOLDER**

(75) Inventors: **John A. Gelardi**, Kennebunkport, ME (US); **James Kostyun**, Pittsfield, MA (US); **Kenny Freitag**, Cheshire, MA (US)

D392,500 S 3/1998 McEwan
5,740,155 A 4/1998 Spector
D395,190 S 6/1998 Roth et al.
5,799,784 A * 9/1998 Bosworth 206/308.1

(Continued)

(73) Assignee: **MeadWestvaco Corporation**, Glen Allen, VA (US)

FOREIGN PATENT DOCUMENTS

EP 0233163 A1 8/1987

(**) Term: **14 Years**

(Continued)

(21) Appl. No.: **29/281,239**

(22) Filed: **Jun. 19, 2007**

(51) **LOC (9) Cl.** **06-02**

(52) **U.S. Cl.** **D6/407**

(58) **Field of Classification Search** D6/407, D6/626-635; 206/307, 307.1, 308.1, 309, 206/311, 312, 313, 310, 751; 211/40, 41.1, 211/41.12; D9/415, 428, 547

See application file for complete search history.

FIG. 1 is a top view of a disc holder;

FIG. 2 is a front view of the disc holder of FIG. 1;

FIG. 3 is a left side view of the disc holder of FIG. 1, the right side being a mirror image;

FIG. 4 is a bottom view of the disc holder of FIG. 1;

FIG. 5 is a back view of the disc holder of FIG. 1;

FIG. 6 is an enlarged sectional view taken across line 6—6 in FIG. 1; and,

FIG. 7 is an enlarged fragmented sectional view taken across line 7—7 in FIG. 1.

The broken lines which illustrate unclaimed structure or define the bounds of the claimed design form no part thereof.

1 Claim, 4 Drawing Sheets
